Primary Examiner — Darcey E Gottschalk(74) Attorney, Agent, or Firm — Birch, Stewart, Kolasch & Birch, LLP(57) CLAIM

The ornamental design for a lid, as shown and described.

DESCRIPTION

FIG. 1 is a front, right perspective view of the lid showing my new design;

FIG. 2 is an exploded front view;

FIG. 3 is a rear view thereof;

FIG. 4 is a left side view thereof;

FIG. 5 is a right side view thereof;

FIG. 6 is a top plan view; and,

FIG. 7 is a bottom plan view thereof.

The broken line showing on the lid in the figures is for the purpose of illustrating portions of the lid that form no part of the claimed design; and the broken line showing of the pitcher in the figures is for the purpose of illustrating environment and forms no part of the claimed design.

1 Claim, 7 Drawing Sheets(56)
